UNITED STATES PATENT OFFICE

HERMANN SUIDA, OF MODLING, AUSTRIA, ASSIGNOR TO I. G. FARBENINDUSTRIE AKTIENGESELLSCHAFT, OF FRANKFORT-ON-THE-MAIN, GERMANY, A CORPORATION OF GERMANY

MANUFACTURE OF ISOPROPYL- AND HOMOLOGOUS ESTERS OF ALIPHATIC ACIDS AND ISOPROPYL- AND HOMOLOGOUS ALCOHOLS

No Drawing. Application filed July 24, 1929, Serial No. 380,748, and in Austria July 21, 1928.

The invention relates to the manufacture of isopropyl-, sec.-butyl- and homologous esters of aliphatic acids soluble in water, as well as isopropyl-, sec.-butyl- and homologous alcohols from dilute aliphatic acids soluble in water and from olefines. I have found that by introducing propylene, butylene or homologues thereof or gases containing such olefines into acetic acid of any dilution or another dilute aliphatic acid soluble in water in the presence of small amounts of mineral acids or strong organic acids with or without the addition of metallic salts as catalysts, at temperatures exceeding 100° C. and super-atmospheric pressure, the acetic or other acid esters of isopropyl-, sec.-butyl- and the homologous alcohols are obtained as well as the corresponding alcohols. A special method of carrying out the above process consists in causing dilute acetic acid and olefine gases to react with one another in a continuous process at temperatures exceeding 100° C. in the presence of the auxiliary agents mentioned above at such a pressure that the esters and alcohols formed distil continuously into an upright receiver kept under pressure, while the auxiliary agents hereinbefore referred to, in so far as they are not used up in the reaction, remain behind in the reaction vessel.

In accordance with the invention acetic acid of any dilution or another dilute aliphatic acid soluble in water reacts readily with olefines with the exception of ethylene at temperatures exceeding 100° C. and super-atmospheric pressure above 10 atmospheres with the simultaneous formation of esters and alcohols, provided that a small amount of strong acid is present as catalyst. Indeed olefines with the exception of ethylene even react on dilute acetic acid at elevated temperatures and pressures in the absence of strong acids as catalysts, although a technically satisfactory result is only obtained in the presence of strong acids. In order to exclude the known reaction between olefines and strong acids it will be understood that the catalytically acting strong acid is only added in quite small quantities say, 5 per-

cent or less and is still further diluted by the dilute acid.

As such catalytically acting strong acids the following are named among others:— hydrochloric acid, sulphuric acid, phosphoric acid, naphthalene sulphonic acid, benzene sulphonic acid, trichloracetic acid.

The presence of metallic salts exerts under given conditions a favorable influence on the progress of the reaction, in particular silver salts and copper salts react favorably; the influence of these metallic salt catalysts, however, is so small in comparison with the influence of small amounts of strong acid that the practical execution of the reaction can only be carried out in the presence of a catalytically acting amount of the above strong acids.

The technical progress and success of this process is based on the fact that dilute waste acetic acid or other aliphatic dilute acid soluble in water, such as formic or propionic acid, for example, 10%, 15%, 20%, 30% acetic acid, as is obtained as an undesirable and difficultly utilizable by-product in all kinds of acetylation, can be converted continuously with gases containing olefines in such a way that the acetic acid is transformed to readily separable, highly valuable esters and simultaneously the water from the dilute acetic acid is converted in large measure into the alcohols corresponding to the olefines, while the remaining part of the water from the dilute acetic acid distils over with the esters and alcohols. Conversely the strong acid used as catalyst remains behind in the reaction mass, is not used up and serves continually for the reaction of fresh quantities of dilute acid with olefines.

The reaction can be carried out in an acid and pressure proof apparatus either intermittently or continuously, the continuous process being particularly economical; for example, the process can be carried out by erecting on the reaction vessel a rectifying column, which is likewise maintained under pressure, and joining thereto a receiver under pressure, the temperature of which is regulated to comply with the requirements. The pressure reaction vessel is charged with dilute acetic acid or other aliphatic acid solu-

ble in water and a small amount of a strong non-volatile acid. A suitable reaction temperature is fixed, the olefine or olefine mixture is forced through the reaction liquid and dilute acetic acid pumped in at the same rate as the ester, alcohol and some water distil off. The ester and alcohol formed as well as some water, which distils with them accumulate in the pressure receiver and excess olefine escapes continuously by a valve in the pressure receiver. The pressure receiver is emptied either continuously or intermittently. The olefine flowing away from the pressure receiver is reabsorbed in the process. The catalytically acting strong acid in the reaction vessel need not be renewed for a long period.

The invention is illustrated by the following examples:—

20

Example 1

An acid proof autoclave fitted with a stirrer is charged with 15% acetic acid, which contains 3% sulphuric acid, the temperature is increased with stirring to 150° C. and then propylene or gas containing propylene is forced in under a pressure of over 20 atmospheres so long as a decrease of pressure takes place. After cooling and subsequent removal of gas the isopropyl ester formed is distilled off with the isopropyl alcohol. The ester and alcohol are in the proportion of 1:8.

35

Example 2

The process is carried out in an analogous manner employing 30% acetic acid. In this case the ratio of the ester to alcohol is 1:2.5. Instead of a temperature of 150° C. a temperature lying between 180–200° C. can be selected.

Example 3

A cracking gas containing considerable quantities of propylene, butylene and homologues is passed through a pressure-tight and acid-resisting cylinder, which contains 10% acetic acid and 5% phosphoric acid at a temperature of 180° C. under a pressure of 50 atmospheres. On the top of the pressure vessel a distillation tube is attached, which is cooled in its lower part and ends in a pressure receiver. The residual gas streams continuously through a throttle valve present in the pressure receiver. The receiver is with advantage maintained at 50° C. In the receiver a mixture of esters of acetic acid with alcohols corresponding to the olefines accumulates. The ethylene from the cracking gas takes no part in the reaction but escapes with the residual gas. Instead of phosphoric acid an equivalent quantity of trichloro acetic acid or naphthalene disulphonic acid, benzene sulphonic acid or any similar acid can be used.

Example 4

A pressure vessel in the form of a tube is charged with 20% acetic acid containing 2% of sulphuric acid and 1% of silver acetate. Attached to the pressure vessel is a rectifying column provided with filling materials together with a corresponding reflux condenser. The receiver is attached to the reflux condenser and is likewise maintained under pressure. A gas rich in propylene and butylene (containing about 60–80% of these olefines) is forced in under a pressure at 20 to 50 atmospheres of 180° C. Simultaneously preliminarily heated acetic acid of 20% is pumped in. The mixture of isopropyl and sec.-butyl esters as well as about 80% of isopropyl and sec.-butyl alcohol accumulates in the pressure receiver by a suitable regulation of the reflux condenser, while the residual gas escapes continuously from the pressure receiver through the throttle valve and by washing this gas with water the last traces of alcohol and ester carried away can be extracted. The method of working is continuous throughout and 20% acetic acid is continuously converted into ester and alcohol. The acetic acid is completely utilized and does not escape with the distillate. Instead of using silver acetate as carrier an equivalent quantity of copper acetate can be used.

I claim:

1. The process which comprises reacting with a higher homologue of ethylene upon a liquid comprising a dilute aliphatic acid soluble in water in the presence of no more than 5 per cent of a strong acid, under conditions of elevated temperature above 100° C. and superatmospheric pressure.

2. The process which comprises reacting with a higher homologue of ethylene upon a liquid comprising a dilute aliphatic acid soluble in water in the presence of no more than 5 per cent of a strong inorganic acid, under conditions of elevated temperature above 100° C. and pressure above 10 atmospheres.

3. The process which comprises reacting with a higher homologue of ethylene upon a liquid comprising dilute acetic acid in the presence of no more than 5 per cent of a strong inorganic acid, under conditions of elevated temperature above 100° C. and pressure above 10 atmospheres.

4. The process which comprises reacting with a higher homologue of ethylene upon liquid acetic acid containing less than 30 percent in the presence of at most 5 percent of sulphuric acid at a temperature of at least 150° C. and under a pressure of more than 20 atmospheres.

5. The process which comprises reacting with an olefinic gas containing a higher homologue of ethylene upon a liquid dilute

aliphatic acid in the presence of no more than 5 per cent of a strong acid and a salt of a heavy metal under conditions of elevated temperature above 100° C. and pressure above 10 atmospheres.

5 6. The process which comprises reacting with an olefinic gas containing a higher homologue of ethylene upon liquid dilute acetic acid in the presence of no more than 5 per cent of a strong inorganic acid and a silver salt under conditions of elevated temperature above 100° and pressure above 10 atmospheres.

7. The process which comprises continuously feeding a gas containing a higher homologue of ethylene under conditions of elevated temperature above 150° C. and pressure above 20 atmospheres into a liquid dilute aliphatic acid soluble in water and containing no more than 5 per cent of a strong inorganic acid, the esters and alcohols formed being continuously distilled off under the same pressure and new dilute aliphatic acid being supplied at the rate of the consumption thereof.

8. The process which comprises continuously feeding a gas containing a higher homologue of ethylene under conditions of elevated temperature above 150° C. and pressure above 20 atmospheres into liquid dilute acetic acid containing no more than 5 per cent of a strong inorganic acid, the esters and alcohols formed being continuously distilled off under the same pressure and new dilute acetic acid being supplied at the rate of the consumption thereof.

9. The process which comprises continuously feeding a gas containing a higher homologue of ethylene at a temperature of about 180° C. and under a pressure of 20 to 50 atmospheres into dilute acetic acid containing about 20 percent of acetic acid, about 2 percent of sulfuric acid and about 1 percent of silver acetate, continuously distilling off the acetic acid esters and the non-primary alcohols formed and supplying new dilute acetic acid at the rate of the consumption thereof.

In testimony whereof I have hereunto set my hand.

HERMANN SUIDA.
